(57) **CLAIM**

We claim the ornamental design for a wristband for a fitness monitoring capsule, as shown and described.

DESCRIPTION

FIG. 1 is a front view of a wristband for a fitness monitoring capsule.

FIG. 2 is a left side view of the wristband of FIG. 1.

FIG. 3 is a rear view of the wristband of FIG. 1.

FIG. 4 is a right side view of the wristband of FIG. 1.

FIG. 5 is a bottom view of the wristband of FIG. 1.

FIG. 6 is a top view of the wristband of FIG. 1.

FIG. 7 is an isometric view of the wristband of FIG. 1; and, FIG. 8 is an isometric view of the wristband of FIG. 1 with the straps of the wristband clasped together to form a loop that may be worn about a person's wrist.

Stipple shading is used in the accompanying Figures to convey surface contouring, not texture. Features depicted using broken lines and a lack of shading indicate environmental structure that is unclaimed in various embodiments. For example, various logos and other text are shown in broken lines and with a lack of shading; in such cases, the unshaded regions around such logos or text are enclosed in a rectangular border that represents the boundary between a claimed portion of the depicted design and the unclaimed portion of the depicted design.
